The ornamental design for an applicator for electrophoretic transcutaneous delivery of drugs, as shown and described.

DESCRIPTION

FIG. 1 is a top plan view of an applicator for electrophoretic transcutaneous delivery of drugs showing our new design;

FIG. 2 is a bottom plan view thereof;

FIG. 3 is a front elevational view thereof, the rear elevational view being identical thereto;

FIG. 4 is a right side elevational view thereof;

FIG. 5 is a left side elevational thereof; and,

FIG. 6 is a perspective view thereof.

FIG. 1

FIG. 2

FIG. 3

FIG. 4

FIG. 6
